STARLEY F. BEASLEY, OF KANSAS CITY, KANSAS, ASSIGNOR OF ONE-HALF TO FRANK E. WELLMAN, OF KANSAS CITY, KANSAS.

DRAFT-GEAR CARRIER IRON AND TANK-BAND ANCHOR.

Application filed December 20, 1926. Serial No. 156,039.

This invention relates to draft gear construction and more especially to the rear carrier iron construction thereof.

The conventional type of carrier irons are made of wrought iron of $\frac{3}{4}$ " to 1" in thickness, which type of carrier iron is unsatisfactory because it becomes worn in a relatively short time under the sliding actions thereon of the coupler yoke containing the draft gear, and bends downward and hence throws the draft gear out of alignment with the coupler. Under such conditions, carrier irons must be replaced at relatively frequent intervals as otherwise more expensive replacements become necessary.

It is common practice in tank cars to utilize the ends of the rear carrier irons as points of anchorage for tank bands, and when such an iron becomes weakened by wear its tendency to bend under the weight of the yoke and draft gear is augmented by upward pull upon the ends of the iron by the connected tank band, as in the progress of a car, upward movements of the tank result in the application of leverage by the band on the ends of the iron, which upward pull not only has a tendency to bend the iron downward at its middle but also to more quickly loosen the bolts or rivets fastening the band to the draft sills of the car if the resistance of the iron is lessened by the weakening and sagging of its central portion.

My object is to provide a rear carrier iron adapted—without undue weight—to resist bending strains due to the weight of the yoke and draft gear and the upward pull of the tank band, and provided with a replaceable leveling shoe so that in the event of appreciable wear of the latter, it can be quickly and easily replaced, the replacement of such shoe being also desirable for leveling purposes in the event the front carrier iron becomes unduly worn. A carrier iron construction of the type comprehended is furthermore desirable as it becomes a permanent part of the car and is much more economical in service and of greater strength than carrier irons of the conventional type above referred to.

With the object mentioned in view, the invention consists in certain novel and useful features of construction and combinations of parts as hereinafter described and claimed;

and in order that it may be fully understood, reference is to be had to the accompanying drawing, in which:

Figure 1 is a vertical longitudinal section through a part of a car frame and centrally through the rear carrier iron embodying the invention.

Figure 2 is a vertical section on the line II—II of Figure 1.

Figure 3 is an enlarged top plan view of the carrier iron.

Figure 4 is a central section taken longitudinally thereof.

Referring to the drawing in detail, 1 indicates a part of a car frame construction and 2 the center or draft sills thereof.

3 indicates the rear carrier iron, the same being of channelled form to provide for stiffness and strength without undue weight. Formed on the upper side of the carrier iron and spaced equal distances from the longitudinal center of the car frame are pairs of spaced lugs 4, the lugs at corresponding sides of the center being spaced apart to provide interposed openings 5. The two sets of lugs 80 provide between them a centralizing chamber 6, and seated within said chamber upon the carrier iron body is a flat plate or shoe 7 having lugs 8 engaging the openings 5 so that it shall be impossible for the shoe 85 to slide from position, as hereinafter referred to.

To utilize the carrier iron as an anchorage, its ends are sloped downwardly as at 9 and perforated to receive the bolt terminals 10 of a band 11 for encircling the tank, not shown, the terminals being engaged at the under side of the arms 9 by retaining and lock nuts 12.

The draft gear 13 which may be of any suitable or preferred type as it forms no part of this invention, is indicated generally at 13, and forming a part of the draft gear is a conventional yoke 14 which rests upon the shoe 7, and is adapted in the travel and startings and stoppings of the car to slide upon said plate or shoe, the yoke forming in effect a continuation or extension of the shank 15 of the coupler, not shown. It will be apparent that when the wear on the shoe 105 becomes sufficient to disturb the alinement between the draft gear and coupler, the shoe can be readily replaced without necessitating removal or detachment of the carrier iron, and that should the front carrier iron, not 110

shown, become materially worn so as to affect the alinement mentioned, a thicker shoe may be placed in position for the purpose of maintaining the level or alinement of the draft gear and coupling. These difficulties are encountered in practice and with the conventional type of carrier irons mentioned cannot be rectified without considerable trouble and a great deal more expense than the correction can be made where a carrier iron provided with a replaceable shoe, as described, is employed. It will also be apparent that by the provision of a carrier iron which will not readily bend, the leverage of the upward pull of the band tending to loosen the rivets or bolts uniting the carrier iron to the sills is minimized, and it is also clear that the use of a channelled carrier iron in conjunction with a replaceable shoe enables the use of carrier irons of lighter construction than those commonly employed.

The back and forth movements of the yoke on the shoe obviously cannot dislodge the latter, as the said lugs 8 by engagement with the opposing lugs 4, hold it practically stationary.

From the above description it will be apparent that I have produced a carrier iron construction embodying the features of advantage set forth as desirable in the statement of the object of the invention, and

which is susceptible of modification in minor particulars without departing from the principle of construction and mode of operation involved.

What I claim is:

1. A carrier iron provided with two sets of upwardly projecting guide lugs, the two sets being spaced apart laterally, and the lugs of each set spaced apart longitudinally, in combination with a shoe fitting flatly on the carrier iron between the laterally spaced lugs, and provided with outwardly projecting lugs fitting in the spaces between the longitudinally spaced lugs.

2. The combination with the draft sills of a car, of a carrier iron bridging the space between and secured to the lower edges of the draft sills and of longitudinally channelled construction, the carrier iron being provided with a plurality of upstanding lugs within the channel formed between said draft sills, said lugs being arranged in two sets spaced apart laterally, and the lugs of each set being spaced apart longitudinally, and a shoe fitting flatly on the carrier iron between the laterally spaced lugs, and provided with outwardly-projecting lugs fitting in the spaces between the longitudinally spaced lugs.

In witness whereof I hereunto affix my signature.

STARLEY F. BEASLEY.
